MACHINE FOR MAKING PREBUILT
BORDERS FOR MATTRESSES

Sidney Schwartz, Detroit, Mich.

Application December 6, 1948, Serial No. 63,667

7 Claims. (Cl. 112—2)

1

My invention relates to a machine for making pre-built borders for mattresses.

An important object of the invention is to provide a machine of the above mentioned character for use in connection with a standard sewing machine, which sewing machine may be readily applied in position and removed therefrom, as desired.

A further object of the invention is to provide a machine of the above mentioned character wherein the sewing machine is held stationary and the work is shifted longitudinally and laterally with respect to the sewing machine.

A further object of the invention is to provide means for transversely reciprocating the work with respect to the sewing machine and effecting an intermittent longitudinal feed of the work at the end of each transverse stroke.

A further object of the invention is to provide a machine of the above mentioned character which is of simplified construction and is relatively inexpensive to manufacture and automatic and reliable in operation.

Other objects and advantages of the invention will be apparent during the course of the following description.

In the accompanying drawings, forming a part of this application, and in which like numerals are employed to designate like parts throughout the same.

Figure 1 is a side elevation of a machine embodying my invention.

Figure 2 is a plan view of the same.

Figure 3 is a transverse vertical section taken on line 3—3 of Figure 2, the carriage being shifted to the left.

Figure 4 is a similar view with the carriage shifted to the right.

Figure 5 is a transverse section taken on line 5—5 of Figure 1.

Figure 6 is a vertical section taken on line 6—6 of Figure 5.

Figure 7 is a fragmentary plan view of the border produced by the normal operation of the machine.

Figure 8 is a similar view of the border produced by an adjustment of the machine, and,

Figure 9 is a similar view showing a border produced by a further adjustment of the machine.

In the drawings, where for the purpose of illustration is shown a preferred embodiment of my invention, the numeral 20 designates a carriage which is shiftable laterally and held against longitudinal displacement. The carriage comprises a lower horizontal frame 21, supported by

2

wheels 22, traveling upon stationary tracks 23. The carriage further comprises a vertical frame 24, rigidly mounted upon the horizontal frame, nearer one longitudinal edge thereof. Extending into the upper portion of the vertical frame 24 and above the horizontal frame 21, is a horizontal table top 25 which is stationary and supported by legs 26 and diagonal braces 27. The table top 25 extends into the central open space of the vertical frame 24 and will clear this frame during the transverse reciprocation of the carriage. Mounted upon the stationary top 25 is a sewing machine 28, of any well known or preferred type. This sewing machine includes the usual arm 29 and head 30. The sewing machine is arranged upon the table top so that the longitudinal axis of the arm 29 extends transversely of the carriage 20 or longitudinally of the direction of reciprocation of this carriage. The sewing machine includes the usual reciprocatory needle and the usual presser foot used in sewing quilting. The machine will sew the line of stitching in any direction, depending upon the movement of the work with respect to the needle. The conventional feed dog of the sewing machine may be removed as separate means are provided to feed the work longitudinally of the carriage. Since the table 25 is stationary, the sewing machine is held stationary. This construction is advantageous inasmuch as it eliminates any special mounting for the sewing machine, as is done when the sewing machine is reciprocated. It also permits of the sewing machine being readily separated from the table top so that such sewing machine may be used for other purposes if desired or a different sewing machine substituted therefor. The sewing machine 28 may be driven continuously by a separate motor 31.

The carriage 20 embodies a shelf 32 upon which the folded ticking 33 may be supported and this ticking is passed about guide rollers 34 and 35, mounted upon the vertical frame 24. The numeral 36 designates a roll of inexpensive fabric, such as tobacco cloth, cheesecloth, or the like. The fabric 36 is passed about a guide roller 37 also mounted upon the upper end of the vertical frame 24. The carriage further embodies a shelf 38 for supporting cotton wadding or batting 39, which is passed over the fabric 36, beneath the fabric 33 and over the guide roller 37. The fabrics 33 and 36 pass from the roller 37 in superposed relation and the wadding or batting 39 is arranged between these fabrics, and the assembled fabrics and batting then pass beneath a transverse guide roller 40, arranged near and

above the table top 25, to position the assembled work layers flat upon the table top 25. The assembled layers of the work will slide as a unit upon the table top, longitudinally or transversely of the table top. The work discharges from the table top 25 and passes between a pair of opposed feed rollers 41 and 42. The vertical frame, at the discharge side of the feed rollers, may be equipped with a table top 43, for supporting the finished work which will discharge downwardly from the table top and may be collected in a box or basket 44. The feed rollers 41 and 42 are employed to feed the work longitudinally, intermittently, and the lower roller 42 is driven for this purpose, as will be explained.

Mounted within the central open space of the vertical and horizontal frames of the carriage 20 is a stationary horizontal base or beam 45. Mounted upon the stationary base 45 is a fixed bearing 46, holding a horizontal rotatable shaft 47, held against longitudinal displacement. A companion fixed bearing 48 is mounted upon the stationary base 45 and holds a rotatable shaft 49, also held against longitudinal displacement. Rigidly mounted upon the shaft 47 is a sprocket wheel 50 and a sprocket wheel 51 is rigidly mounted upon the shaft 49 and an endless sprocket chain 52 is passed about these sprocket wheels 50 and 51. The shafts 47 and 49 extend longitudinally of the frame 20, while the sprocket chain 52 extends transversely of the carriage, as shown. The shaft 47 is driven by gearing 53, which in turn may be driven from a motor 54. Any suitable type of speed reducing gearing may be employed.

In order that the carriage 20 may be reciprocated transversely by the continuous travel of the endless chain 52 in one direction, the carriage has a pair of spaced superposed horizontal bars 55 and 56 rigidly secured thereto, and these bars extend transversely of the carriage and longitudinally of the endless sprocket chain 52, above and below the same. The bars 55 and 56 reciprocate with the carriage while the shafts 47 and 49 remain in a fixed location. The bar 55 has a depending peg or extension 57 rigidly secured thereto and the bar 56 has an upstanding peg or extension 58 rigidly secured thereto. The pegs 57 and 58 are vertical and are longitudinally staggered with respect to bars 55 and 56, Figure 5. The pegs 57 and 58 are arranged to be engaged by a horizontal pin 59, rigidly secured to the sprocket chain 52, as will be explained.

Extending transversely of the carriage 20 and mounted in bearings 60 secured to the carriage is a shaft 61, disposed transversely of the carriage and at right angles to the shafts 47 and 49. This shaft is arranged near the endless sprocket chain 52 and is parallel therewith. The shaft 61 has a sprocket wheel 62 rigidly secured thereto, engaged by a sprocket chain 63, engaging a sprocket wheel 64, mounted upon a transverse shaft 65, supporting and driving the lower feed roll 42. It might be stated that the shaft 61 is intermittently turned and this operates the feed rollers 41 and 42 to intermittently feed the work. Rigidly mounted upon the shaft 61 is a disc 66, having four pins 67 rigidly secured thereto and extending axially thereof. These four pins are arranged 90 degrees apart, whereby the pins are disposed in diametrically opposite pairs. A straight bar 68 is rigidly mounted upon the shaft 61 and has a pair of diametrically oppositely arranged pins 69 rigidly mounted thereon and extending axially of the shaft 61. The elements 70

66 and 68 are spaced longitudinally of the shaft 61 for a distance corresponding generally to the length of the endless chain 52. The sprocket chain 52 has horizontal transverse pins 70 and 71 rigidly secured thereto and projecting laterally beyond same for co-action with the pins 67 and 69, as will be explained.

The operation of the machine is as follows:

It will be assumed that the work has been passed beneath the presser foot of the sewing machine and is engaged between the feed rollers 41 and 42. The sewing machine is constantly operating and the shaft 47 is continuously driven clockwise, Figures 1, 2, 3 and 4, and counterclockwise, Figure 5. The pin 59 which is now at the lower rung of the endless chain 52, is brought into engagement with the lower peg 58, and the carriage is shifted to the extreme left, Figure 3. When this position is reached, the pin 59 travels about the sprocket wheel 51, Figure 5, and disengages the lower peg 58. The carriage is now at rest and will remain at rest until the pin 59 engages behind the upper peg 57. While the carriage is thus at rest in the extreme left position, the pin 70 is traveling downwardly about the sprocket wheel 50 and will engage the pin 67, turning the disc 66, turning the shaft 61, which in turn turns the lower feed roller 42 to feed the work a step. By the time the pin 59 engages the upper peg 57, the pin 70 has moved the pin 67 to the lowermost position and the horizontal travel of the run of the sprocket chain 52 will move the pin 70 horizontally out of engagement with the pin 67. The carriage is now being shifted to the right and the extreme right position is shown in Figure 4. When the extreme right position, Figure 4, is reached, the pin 59 is passing downwardly over the sprocket wheel 50, at which time the pin 59 will disengage the upper peg 57, and the carriage will be at rest, while the pin is traveling about the sprocket wheel 50. The pin 71 is now in proximity to the bar 68, which has been shifted to the right and when the pin 71 travels downwardly about the sprocket wheel 50, the pin 71 engages the pin 69 of the bar 68, during the rest period of the carriage, turning the bar 68 and shaft 61 and effecting the next intermittent movement of the feed roller 42. When the pin 59 again reaches the lowered position, it will engage behind the peg 58 and the carriage is again shifted to the left and the operation is repeated. It is thus seen that the carriage is shifted transversely in one direction and stopped, and then the work is fed longitudinally a step and the carriage then shifted transversely in the opposite direction and stopped and the work fed a step, and this cycle of operation is repeated. This results in the intermittent longitudinal feed of the fabric and between the intermittent longitudinal feed, the fabric is shifted transversely with respect to the sewing machine. A line of stitching is produced including transverse portions 72 and longitudinal portions 73, or a series of transverse U-shaped portions connected at their ends, Figure 7.

I contemplate removing the bar 68 and pins 69, and when this is done, the alternate feeding of the fabric caused by the action of the bar 68 is dispensed with and the line of stitching 74 shown in Figure 8 is provided, including U-shaped portions having transverse portions 75 which are sewed into or over each other.

I also contemplate operating the machine so that the work may be provided with longitudinal lines of stitches 76 instead of transverse stitches.

To do this, the rotation of the shaft 47 is stopped and the shaft 61 is continuously driven, which may be effected by a gear 77 mounted thereon. The sewing machine then will produce the longitudinal continuous lines of stitching since the work is fed longitudinally continuously without the transverse shifting of the work. When the machine is used in this way, I contemplate employing a sewing machine having a plurality of needles so that a plurality of lines of stitches is produced at one time.

The sewing machine used to produce the transverse and longitudinal lines of stitching has the ordinary feed dog mechanism removed, as the feeding is effected by the shifting of the work bodily by means of the carriage and the intermittent rotating of the feed rolls while the sewing machine remains stationary. Any suitable type of sewing machine may be employed which will sew and permit of the work being shifted in different directions.

It is to be understood that the form of my invention herewith shown and described is to be taken as the preferred example of the same and that various changes in the shape, size and arrangement of parts may be resorted to without departing from the spirit of my invention or the scope of the subjoined claims.

Having thus described my invention, I claim:

1. A machine for making pre-built borders for mattresses, comprising a stationary support for a sewing machine, a carriage arranged near the support, work guiding and feeding means mounted upon the carriage to engage with the work and feed it longitudinally, a shaft arranged near the carriage and extending transversely of the line of work feed, a stationary supporting member mounted near the carriage, an endless operating member carried by the stationary supporting member and extending longitudinally of the shaft, means to reciprocate the carriage in a direction longitudinally of the shaft including an element secured to the endless operating member, radial members mounted upon the shaft, pins mounted upon the radial members, pins mounted upon the endless operating member to co-act with the first named pins, and a driving connection between the shaft and the feeding means for the work.

2. A machine for making pre-built borders for mattresses, comprising a stationary support for a sewing machine, a shiftable carriage arranged near the support, work guiding and feeding means mounted upon the carriage to engage with the work and feed it longitudinally, a shaft mounted upon the carriage to move therewith and extending transversely of the line of work feed, upper and lower pegs secured to the carriage, an endless operating member having a pin to engage the pegs, radial members axially spaced upon the shaft and mounted thereon for rotation therewith, pins carried by the radial members, pins secured to the endless operating member for co-action with the pins of the radial members, and a driving connection between the shaft and the work guiding and feeding means.

3. A machine for making pre-built borders for mattresses, comprising a stationary support for a sewing machine, a carriage arranged near the support and shiftable with relation thereto, work guiding and feeding means mounted upon the carriage to engage with the work and feed it longitudinally, a shaft mounted upon the carriage to move therewith and extending transversely of the line of work feed, upper and lower

pegs secured to the carriage, an endless operating member arranged near the shaft and extending longitudinally thereof, a stationary supporting member, wheels mounted upon the stationary supporting member and receiving thereon the endless operating member, a pin carried by the endless operating member to engage with the upper and lower pegs of the carriage, radial members mounted upon the shaft and axially spaced thereon, pins mounted upon the radial members and extending axially of the shaft, pins mounted upon the endless operating member to engage with the pins of the radial members, and a driving connection between the shaft and the guiding and feeding means.

4. A machine for making pre-built borders for mattresses, comprising a stationary support for a sewing machine, a carriage mounted near the support and shiftable with relation thereto, work guiding and feeding means mounted upon the carriage to engage with the work and feed it longitudinally, a shaft mounted upon the carriage to move therewith and extending transversely of the line of work feed, upper and lower pegs secured to the carriage, a stationary supporting member, an endless operating member mounted upon the stationary supporting member and arranged near the shaft and extending longitudinally thereof, a pin carried by the endless operating member to engage with the pegs, a radial member mounted upon the shaft, pins mounted upon the radial member and extending axially of the shaft, pins mounted upon the endless operating member to engage with the pins of the radial member, and a driving connection between the shaft and the guiding and feeding means.

5. A machine for making pre-built borders for mattresses, comprising a stationary support for a sewing machine, a transversely shiftable carriage arranged near the support, work guiding and feeding means mounted upon the carriage to feed the work longitudinally of the carriage, a shaft mounted upon the carriage and extending transversely thereof, means engaging the carriage to shift it transversely, an endless operating member arranged near the shaft and extending longitudinally thereof, a radial member mounted upon the shaft, pins carried by the radial member and extending axially of the shaft, a pin mounted upon the endless operating member to engage with the axially extending pins, and a driving connection between the shaft and the work guiding and feeding means.

6. A machine for making pre-built borders for mattresses, comprising a relatively stationary sewing machine, a carriage arranged near the sewing machine, work guiding and feeding means mounted upon the carriage to feed the work longitudinally of the carriage, means to reciprocate the carriage transversely with relation to the longitudinal feed of the work, a rotatable shaft mounted upon the carriage and extending transversely thereof, an elongated endless operating member arranged near the shaft and extending longitudinally thereof, means to drive the elongated endless operating member, radial members mounted upon the shaft and axially spaced thereon for a distance approximately equal to the length of the elongated endless operating member, pins carried by the radial members and extending axially of the shaft in the same direction, spaced pins mounted upon the endless operating member to engage with the axially extending pins, and driving connecting means between the shaft and the work guiding and feeding means.

7. A machine for making pre-built borders for mattresses, comprising a relatively stationary sewing machine, a carriage arranged near the sewing machine, work guiding and feeding means mounted upon the carriage to feed the work longitudinally, means to mount the carriage for reciprocatory transverse movement transversely with relation to the longitudinal feed of the work, a rotatable shaft mounted upon the carriage and extending transversely of the carriage and the longitudinal feed of the work, an elongated endless operating member arranged near the shaft and extending longitudinally thereof, means operated by the endless operating member to reciprocate the carriage transversely, radial members mounted upon the shaft and axially spaced thereon for a distance approximately equal to the length of the elongated endless operating member, pins carried by the radial members and

extending axially of the shaft in the same direction, spaced pins mounted upon the endless operating member to engage with the axially extending pins, and driving connecting means between the shaft and the work guiding and feeding means.

SIDNEY SCHWARTZ.
